UNITED STATES PATENT OFFICE.

SAMUEL ROBERT BELL, OF TUSCALOOSA, ALABAMA.

SUSPENSORY DEVICE FOR ELECTRIC LAMPS.

No. 832,951.

Specification of Letters Patent.

Patented Oct. 9, 1906.

Application filed September 19, 1905. Serial No. 279,078.

To all whom it may concern:

Be it known that I, SAMUEL ROBERT BELL, a citizen of the United States, and a resident of Tuscaloosa, in the county of Tuscaloosa and State of Alabama, have invented a new and Improved Suspensory Device for Electric Lamps, of which the following is a full, clear, and exact description.

This invention relates to suspensory devices for electric lamps; and it consists, substantially, in the details of construction and combinations of parts hereinafter more particularly described, and pointed out in the claims.

One of the principal objects of the invention is to provide a suspensory device for electric lamps of an embodiment to overcome numerous disadvantages and objections encountered in the use of many other contrivances of the kind hitherto devised.

A further object is to provide a device of this character which is simple in construction and comparatively inexpensive to manufacture, besides being thoroughly effective and reliable in use and possessing the capacity for long and repeated service.

The above and additional objects are attained by means substantially such as are illustrated in the accompanying drawings, in which—

Figure 1 is a vertical sectional view of a suspensory device for electric lamps embodying my improvements. Fig. 2 is a sectional side view. Fig. 3 is a top plan view, and Fig.

4 is an enlarged sectional plan view in detail.

Before proceeding with a more detailed description it may be stated that in the form of my improvements herein shown I employ a suspensory device for electric lamps comprising a specially-constructed spring-constructed drum about or around which is wound a duplex flexible conductor for both supporting an electric lamp and supplying electric current thereto, specially-constructed electrical connections being employed between said drum and one of the terminals of each of the wires forming said conductor. A specially-constructed attaching member for attaching the device to a ceiling or other support is employed, together with special hangers for the drum and special electrical connections between fuses held by such member and the drum, and while I have herein represented my improvements in a certain preferred embodiment it will be understood, of course, that I am not limited thereto in pre-

cise detail, since immaterial changes therein may be made coming within the scope of my invention.

Reference being had to the drawings by the designating characters thereon, 1 represents the base of a rosette of insulating material, having holes 2 therein for ordinary wooden screws (not shown) for securing the same to a ceiling or other support and also having holes 3 therein for the ordinary inside wiring, (not shown,) a cup 4 of insulating material being removably attached to said base in any suitable way and containing fuses, one of which is indicated at 5, in electrical connection with a strip 6 of conducting material within the cup and one of duplicate sets of oppositely-disposed spring-clips 7 and 8, secured to the under side of the base 1 by means of screws 9, (see Fig. 2,) said connection being had through the intermediary of the usual plate *a*, secured in place by screw *b*. Said duplicate sets of clips are for holding in electrical contact therewith bared portions of the usual service-wires for supplying electric current to the lamp (not shown) to be supported by my improved device, it being here mentioned that the said base 1 has pendent from opposite sides thereof parallel hangers 10 of insulating material, the inner sides of which are preferably formed with vertical grooves 11. (See Fig. 1.) The said hangers are formed at or near their lower ends with openings, in which are seated metallic bushings 12, having corresponding horizontally-disposed openings therethrough in which are rotatably received metallic journals 13, partially extending into and projecting from the ends of preferably a solid drum 14 of non-conducting material—as wood, for instance—each end of said drum and a portion of the periphery thereof from each end being recessed to receive an angular metallic member 15, one branch of which is in electrical contact with the journal 13 contiguous thereto and the other branch of which is provided with a screw 16 for securing in electrical contact therewith one of the terminals 17 of one of the wires of a flexible duplex electrical conductor 18, which is wound about the drum 14 and to the free end of which may be electrically attached the electric lamp in a manner well known. The said drum is preferably provided with flanges 19 at its ends to insure the retention of the windings of the flexible duplex conductor thereon, and it will be noted that each bush-

ing 12 has in electrical contact therewith the lower terminal of one of two electrical conductors 20, the upper terminal of which is in similar connection with the corresponding 5 conducting-strip 6 within the fuse-cup, said conductors extending into the fuse-cup through the usual opening 21 therein and portions thereof being housed in the grooves 11 in the hangers.

10 The outer end of one of the journals 13 for the drum 14 is provided with a pinion 22, the teeth of which are engaged by the teeth of a gear-wheel 23, carried by a spindle 24, rotatably mounted on the adjacent or corresponding hanger 10 and to which is fastened in any suitable way the inner end of a coiled spring 25, having its outer end secured to a pin or stud 26, projecting from the said hanger. It will thus be seen that whenever 15 the flexible duplex conductor 18 may be drawn upon to lower the lamp, for instance, the drum will revolve and the spring 25 will be partially wound or placed under tension, thereby imparting thereto a tendency to 20 again wind up said conductor by causing the drum to revolve in the reverse direction through the intermediary of said pinion and gear-wheel.

Practically the entire structure above 30 described is inclosed by a casing 27 of non-conducting material, secured in place in any suitable way—as, for instance, by means of screws 28, (shown in Fig. 3,) but which are preferably omitted from Figs. 1 and 2. The 35 bottom or lower part of said casing is formed with a centrally-disposed opening, surrounded interiorly of the casing by a threaded collar 29, in which is screwed the threaded stem 30 of a plug 31, of rubber or other suitable insulating material, having a V-shaped opening 32 formed vertically in the same, through which the said flexible duplex conductor extends, as shown. For the purpose of securing or fastening this conductor in the different positions to which it may be drawn, so as 40 to prevent the same from being rewound upon the drum through the power of the spring 25, I remove a radial section from the said plug 31, leaving a slot therein, between 45 the sides of which is held a pin 33, on which is loosely held the upper end of a dog 34, against which constantly presses the free portion of a spring 35, secured at 36 to the inner side of the casing alongside the said 50 threaded collar 29. From this construction it is apparent that the duplex conductor 18 may be drawn out to any length desired by simply carrying the same slightly to one side, thus to overcome the pressure of the spring 55 35 against the dog, and then by releasing the conductor the dog will again be carried against the portion thereof within the said V-shaped opening 32, which portion will be confined or wedged in said opening in a manner and for the purpose explained.

Having thus described my invention, I claim as new and desire to secure by Letters Patent—

1. A suspensory device for an electric lamp, comprising a base of insulating material, a 70 cup of insulating material applied thereto, having fuses therein, hangers of insulating material from the base, provided with metallic bushings, a spring-controlled drum of insulating material, having metallic journals 75 rotatably supported by said bushings, a flexible duplex conductor winding upon the drum, duplicate conductors from the cup, in electrical connection with the fuses and said bushings, and electrical connections between 80 the inner terminals of the wires of said duplex conductor and said journals.

2. A suspensory device for an electric lamp, comprising a base of insulating material, a 85 cup of insulating material applied thereto, having fuses therein, hangers of insulating material from the base, provided with metallic bushings, a spring-controlled drum of insulating material, having metallic journals 90 rotatably supported by said bushings, a flexible duplex conductor winding upon the drum, duplicate conductors from the cup, in electrical connection with the fuses and said bushings, and electrical connections between 95 the inner terminals of the wires of said duplex conductor and said journals, said hangers being formed with grooves in which portions of said duplicate conductors are housed.

3. A suspensory device for electric lamps comprising a base of insulating material, a 100 cup of insulating material applied thereto and having fuses therein, hangers of insulating material attached to the base and provided with metallic bushings, a spring-controlled drum of insulating material having 105 metallic journals rotatably received in said bushings, a flexible duplex conductor winding upon the drum, angular conducting members seated in the material of the drum each having one of the arms thereof in contact 110 with one of said journals and having the other arm thereof in contact with one of the inner terminals of the wires of the duplex conductor, and duplicate conductors leading from the cup and electrically connecting said 115 fuses and said bushings.

4. A suspensory device for an electric lamp, comprising a base of insulating material, a cup of insulating material applied thereto and having fuses therein, hangers of insulating material connected with the base and provided with metallic bushings, a spring-controlled drum of insulating material having metallic journals rotatably received in said bushings, a flexible duplex conductor winding upon the drum, angular conducting members seated in the material of the drum, each having one of the arms thereof in contact with one of said journals, and the other arm thereof in contact with the inner terminal of 130

one of the wires of the duplex conductor, and duplicate conductors leading from the cup and electrically connecting said fuses and said bushings, the hangers having grooves therein 5 in which portions of said duplicate conductors are housed.

5. A suspensory device for an electric lamp comprising a base of insulating material for attachment to a support, a cup of insulating 10 material applied thereto and having fuses therein, hangers of insulating material connected with the base and provided with metallic bushings, a drum having metallic journals rotatably supported by said bushings, 15 one of said journals carrying a pinion, a flexible duplex conductor winding upon the drum, angular conducting members embedded in the drum and having one of the arms thereof in contact with said journals, and the other 20 arm thereof in contact with the inner terminals of one of the wires of the duplex conductor, duplicate conductors from the cup and in electrical connection with the fuses and said bushings, and a spring-controlled 25 gear-wheel in engagement with said pinion.

6. A suspensory device for electric lamps

comprising a spring-controlled drum, a flexible duplex conductor winding thereon, an inclosing casing for the device, having an opening in the lower part thereof, a plug fitting, 30 in said opening, having an opening therethrough, together with a radial slot communicating with the second-named opening, and a spring-pressed dog supported in said slot.

7. A suspensory device for electric lamps, 35 comprising a spring-controlled drum, a flexible duplex conductor winding thereon, an inclosing casing for the device, having an opening in the lower part thereof, a plug fitting in said opening, having an opening therethrough, 40 together with a radial slot communicating with the second-named opening, and a spring-pressed dog supported in said slot, said second-named opening being V-shaped.

In testimony whereof I have signed my 45 name to this specification in the presence of two subscribing witnesses.

SAMUEL ROBERT BELL.
